[57] CLAIM

The ornamental design for a combined speaker box and screen for a television projector, as shown and described.

DESCRIPTION

FIG. 1 is a front, top and right side perspective view of a combined speaker box and screen for a television projector showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a front, top and right side perspective view of a second embodiment of our new design, the other views being the same as FIGS. 3-7.

FIG. 2

FIG. 3

FIG. 4

FIG. 5

FIG. 6

FIG. 7

FIG. 8
